UNITED STATES PATENT OFFICE.

ABRAHAM COOPER, OF BROOKLYN, NEW YORK.

DESIGN FOR AN ELECTRIC-LIGHTING FIXTURE.

Application filed February 12, 1926. Serial No. 16,504. Term of patent 7 years.

To all whom it may concern:

Be it known that ABRAHAM COOPER, a citizen of the United States, and resident of Brooklyn, in the county of Kings and State of New York, has invented a new, original, and ornamental Design for Electric-Lighting Fixtures, of which the following is a specification, reference being had to the accompanying drawing, forming part thereof, in which—

Fig. 1 is a front elevational view of the

electric lighting fixture embodying my new design.

Fig. 2 is a side elevational view thereof.

I claim:

The ornamental design for an electric lighting fixture, as shown.

Signed at New York, county of New York, State of New York.

Dated February 10, 1926.

ABRAHAM COOPER.
